UNITED STATES PATENT OFFICE.

ISAAC W. BOATMAN, OF SEVEN MILE, OHIO, ASSIGNOR OF ONE-HALF TO
YINGLING & BROTHER, OF SAME PLACE.

SOIL-DRESSING MACHINE.

SPECIFICATION forming part of Letters Patent No. 319,949, dated June 16, 1885.

Application filed April 20, 1884. (No model.)

To all whom it may concern:

Be it known that I, ISAAC W. BOATMAN, of Seven Mile, Butler county, Ohio, have invented certain new and useful Improvements 5 in Soil-Dressing Machines, of which the following is a specification.

This invention relates to a machine for finely dressing the plowed soil and furrow-marking the same at one passage of the machine.

10 The improvements will be clearly understood from the following description, taken in connection with the accompanying drawings, in which—

Figure 1 is a side view of a machine embodying my improvements; Fig. 2, a plan of 15 the same with portions broken away, and Fig. 3 a transverse section upon a comparatively large scale of one of the cutter-teeth.

In the drawings, A represents a supporting main roll or ground-wheel of the machine; B, a boxing over the same; C, an end piece of the boxing forming the axle-supports of the roll A; D, a tongue rigidly secured to the boxing B; E, a double-tree; F, tongue-braces; 25 G, draft-chains reaching from the ends of the double-tree rearward to the boxing; H, a post projecting upward from the center of the boxing; I, a seat-bar located above the tongue and in line with the tongue and freely pivoted to 30 the top of the post H, the axis of the pivot being parallel with the axis of the roll A; J, a driver's seat fitted to slide freely along the bar I; K, a removable stop-pin in the rear end of the bar I, serving to prevent the seat 35 sliding clear off the bar; L, a rectangular horizontal frame provided with teeth and pivoted to the roll structure, in front of which it is located; M, connecting-bars freely pivoted at their rear ends to the roll structure; N, bolts passing through slots in the front ends 40 of bars M, and serving as a means for adjustably securing the bars to the frame L; O, bolts aiding in securing the bars M to the frame L; P, holes at the front end of the sides 45 of the frame L corresponding to the rear holes of the bolts N and O; Q, side pieces of the frame L; R, vertically adjustable gaging-wheels located near the front of the frame L; S, T, and U, the main bars of the frame L, 50 lying parallel with the axis of the roll; V, a series of inclined cutter-teeth secured like

harrow-teeth in the bar S; W, harrow-teeth secured in the bar T and set intermediately with reference to the cutter-teeth; X, a leveling-scraper secured to the front edge of bar 55 U; Y, a pair of furrowing-markers secured to the bar T; Z, pivoted connecting-bars reaching from the front end of bar I downward to the frame L, being attached at the frame L to a centrally-located bar identical 60 with the side pieces, Q.

The roll structure has its tongue rigidly connected, and consequently the pull of the team is directly upon this roll structure, the chains G serving to transmit the side pull in 65 turning and thus relieving the team from side pull at the end of the tongue. The frame L becomes pushed along in front of the roll structure, and it is free to rise and fall independent of the roll structure, oscillating upon 70 the axis of the roll structure where the connecting-bars M are loosely pivoted. The gaging-wheels R run upon the soil and can be adjusted vertically to regulate the depth of working for the teeth. As the front frame rises and falls, 75 the seat-bar I may oscillate upon its post-pivot. The driver may shift his seat forward along the bar, so as to cause his weight to exert a downward pressure upon the front frame, or he may shift it to the rear of the post H, so as 80 to exert a lifting force to the front frame, or he may shift it directly over the post H, where his weight has no effect whatever upon the front frame. The row of cutter-teeth V are 85 bent rearward, so as to present a runner-like inclination at their faces, and they are of a triangular section, as shown in Fig. 3, presenting acute cutting-edges. The teeth W are ordinary harrow-teeth set to work deeper than the teeth V. The scraper X levels the dressed 90 soil. The furrowing-markers Y are set a proper distance apart to suit the desired marking, and they project below the scraper. The dressing-frame, it will be seen, is pushed along in front of the roll structure, and it is not affected vertically by the draft of the team. The cutter-teeth cut the larger clods, their inclined faces serving to cause them to cut through clods which, were their cutting faces vertical, they would tend to push in front of them. The 95 harrow-teeth are thus called upon to dispose only of clods of manageable size. The

scraper levels the dressed soil nicely, leaving neat and sharply-defined marker-furrows, and the roll structure gives the dressed soil a final pressing, though the roll structure is not used 5 to act as a land-roller, its purpose being simply to form a wheeled structure to which the draft may be applied and by which the dressing-frame may be pushed, and by which the post-pivot of the lever I may be supported. More 10 bars T with their harrow-teeth may be provided in the front frame, if desired. By means of the slot and bolt N and the adjustable wheels R the front frame may be adjusted vertically with reference to the depth of working. The 15 connecting-bars Z are provided with cross-holes, in any one of which a pin may be placed under or over the tongue, whereby the entire structure may be deprived of its articulation, as may be desired, when the front frame is 20 lifted for leaving the field, or when the front frame is to be held firmly down for dressing peculiar soils.

When the machine is to be used as a drag-harrow, the roll structure goes in front of the 25 frame L, as indicated by the dotted circle a, the bars M and the seat-bar I being reversible to permit of the change.

A combined roller and harrow has been heretofore devised and patented in which the 30 tongue was pivoted to the roller-axis, and in which several harrow-bars located in front of the roller were connected by drag-bars to hooks in the tongue in front of them. In this device any variation in the height of the neck-yoke 35 altered the line of draft of the harrow-bars. I disclaim such device as of my invention. A device has also been contrived and patented in which a harrow is drawn to the rear of the roller. I disclaim such as of my invention. 40 Another device, also patented, exhibits a draft-

frame connected by free links to a roller placed behind, a harrow-frame located within the draft-frame and connected by hinge-like devices, and a tongue pivoted to the front of the draft-frame. In this device the angle of draft 45 varies with every vertical position of the front end of the tongue. I disclaim such as of my invention.

I claim as my invention—

1. In a soil-dressing machine, the combination of the rigid-tongued roll structure, a seat-bar pivoted with reference thereto, a front frame provided with teeth and articulated to the roll structure, the gaging-wheels R, the shifting seat J, and the connecting-bars Z, substantially as and for the purpose set forth. 50

2. The rigidly-tongued roll structure, the soil-dressing frame L, connected thereto in front by pivoted bars, the front row of inclined cutter-teeth V, and one or more rows of harrow-teeth, W, and the scraper X to the rear of the harrow-teeth, combined substantially as and for the purpose set forth. 60

3. The rigidly-tongued roll structure, the soil-dressing frame L, connected thereto in front by pivoted bars, the front row of inclined cutter-teeth V, the rear row of harrow-teeth W, the scraper X, and the markers Y, combined substantially as and for the purpose set forth. 65

4. In a soil-dressing machine, the roll structure, the reversible bars M, pivoted thereto, and the soil-dressing frame fitted to have secured to its front and rear ends alternatively said connecting-bars, combined substantially 70 as and for the purpose set forth. 75
